UNITED STATES PATENT OFFICE

106,980

DESIGN FOR A HOLLOW GLASS BUILDING BLOCK

David Jones, Muncie, Ind., assignor to Owens-Illinois Glass Company, Toledo, Ohio, a corporation of Ohio

Application September 30, 1937, Serial No. 71,904

Term of patent 14 years

To all whom it may concern:

Be it known that I, David Jones, a citizen of the United States, residing at Muncie, in the county of Delaware and State of Indiana, have invented a new, original, and ornamental Design for a Hollow Glass Building Block, of which the following is a specification, reference being had to the accompanying drawing, forming a part thereof.

In the drawing:

Fig. 1 is a perspective view of a hollow glass building block showing my new design, a portion of the block wall being removed to more clearly reveal the nature of a prism arrangement which is a feature of my design.

Fig. 2 is an enlarged fragmentary front elevational view of the block showing one corner thereof; and

Fig. 3 is a greatly enlarged fragmentary horizontal sectional view taken through the block on a plane perpendicular to the front face thereof and further illustrating the prism arrangement.

I claim:

The ornamental design for a hollow glass building block, substantially as shown and described.

DAVID JONES.
